CHILD'S PLAYHOUSE SCREEN

Hans G. Valentine, Milwaukee, Wis.

Application February 2, 1949, Serial No. 630

Term of patent 14 years

(Cl. D34—15)

To all whom it may concern:

Be it known that I, Hans G. Valentine, a citizen of the United States, residing at Milwaukee, in the county of Milwaukee and State of Wisconsin, have invented a new, original, and ornamental Design for a Child's Playhouse Screen, of which the following is a specification, reference being had to the accompanying drawing, forming part thereof.

Figure 1 is a front elevational view of a child's playhouse screen, showing my new design.

Figure 2 is a top plan view thereof.

Figure 3 is a rear elevational view of the screen.

I claim:

The ornamental design for a child's playhouse screen, as shown.

HANS G. VALENTINE.
